GLUING STAND

Ruby R. Roloson, Los Angeles, Calif.

Application June 12, 1943, Serial No. 490,650

5 Claims. (Cl. 144—288)

This invention is directed to an improvement in gluing stands, wherein means are provided for materially simplifying and reducing the labor of the operator in handling and applying glue singly or simultaneously to a plurality of similar objects.

In many industries, particularly in the manufacture of aeroplanes, furniture, and other articles where relatively small strips or pieces of wood are employed, it is customary to unite such pieces with other parts by gluing. This requires the provision of tables or other supports for the articles to which the glue is to be applied, and the rather messy and time-consuming labor of applying the glue. As the glue is ordinarily applied to a number of the objects at one time to save time and labor, the arrangements of the objects in position to receive the glue, the delay in positioning the next group of objects, the inevitable waste of glue in application, and the requirement of a number of workmen to do the job, presents an obvious and real objection to the present accepted type of work in this line.

It is the primary object of the present invention to provide a relatively small, compact, and convenient glue stand, which may be readily moved by the workman from place to place, and in which a considerable number or rows of the objects to which glue is to be applied may be arranged in proper order, and which objects, when so assembled may be moved as a whole to a proper gluing height, successively as required, to thereby permit application of glue to the upper layer, removing such layer of objects when the glue has been applied, raising the successive group to convenient gluing position, and applying glue thereto.

A further object of the invention is the provision in a gluing stand of this type of a platform, capable of being raised or lowered at the will of the operator, and serving to support a successive series or rows of articles to be glued, the platform providing for supporting the uppermost articles above the normal plane of the stand for convenient gluing without wastage, and to raise a successive series of such articles into gluing height when the glue-applied series has been removed.

A further object of the invention is the provision of a slide movable in the stand, and on which gluing accessories, such as a form to receive the glue pot and uprights to receive and support the gluing brush or brushes, with the slide movable beyond the frame to permit con-

venient access to such accessories, or to a position wholly within the plane of the frame, a removable cover plate being provided to close the space containing such accessories when the slide is in inoperative position, to thus protect and prevent contamination of the glue.

The invention is illustrated in preferred form in the accompanying drawings, in which:

Fig. 1 is a view in front elevation of the improved gluing stand.

Fig. 2 is an end view of the same.

Fig. 3 is a section on line 3—3 of Fig. 1.

Fig. 4 is an enlarged elevation, showing the pillar and means for operating the same.

Fig. 5 is a plan view of the slide for carrying the gluing accessories.

Fig. 6 is a transverse sectional view of the adjustable well wall, showing the means for supporting the same.

20 The gluing stand of this invention is in the form of a relatively small frame structure of skeleton make up, including side walls 1, a top 2, and suitable and necessary bracing members. Near the lower ends the side walls are provided with strips 3, spaced apart to provide guides 4 to slidably receive the slide floor 5 on which is arranged the gluing accessories, as will later appear.

25 The top 2, at approximately its center is formed with an opening 6, preferably of narrow elongated form, to receive and guide an upright 7, forming the platform supporting pillar. The opposite narrow end edges of the pillar are formed or provided with teeth 8 and 9, respectively, the teeth on one side, as 8, facing downwardly, while the teeth 9 of the opposite side face upwardly. Thus, by imparting a step-by-step movement to one or the other set of teeth, the pillar may be moved in one direction or the other relative to the stand top.

30 Immediately below the top 2 and forming a rigid part of the frame structure, is a bracing strut 10, one surface of which serves as a guide for the pillar, and to which strut there is secured a guide bar 11, fitting over and guiding the pillar, the strut 10 and guide bar 11 forming a rigid guide in which the pillar moves. The pillar 7 is formed with a longitudinally ranging slot 12, which terminates short of the top and bottom ends thereof. A slide bar 13 is arranged in the slot 12 of the pillar and in a slot of the strut 10, and extends at right angles to and beyond the strut. A plate 14 is secured at the pillar end of the slide bar and overlies the face of the

35 pillar. Springs 15 are secured between the in-

ner end of the slide bar and the frame to yieldingly hold the pillar in proper operating position.

The step-by-step operation of the pillar 1 is provided for through ratchet levers 16 and 17, one on each side of the pillar, with such levers terminally formed for cooperation with a particular set of pillar teeth 8 or 9. That is lever 16, is designed for cooperation with the downwardly-facing teeth 8 and is terminally beveled upwardly to provide a tooth engaging edge, as 18, while the ratchet lever 17 is terminally beveled downwardly to form a tooth engaging edge 19 for cooperation with the teeth 9 of the pillar. Each of the ratchet levers 16 and 17 is movably and pivotally supported on pins 20, projecting from the strut 10, the pins passing through slots 21 in the ratchet levers to permit limited longitudinal movement of such levers. The ratchet levers are connected by a coiled spring 22, terminally secured to the respective levers beyond the slots therein relative to the pillar. The spring serves to tension both ratchet levers toward the pillar and insures tooth cooperation of an operating lever, as will be clear.

The ends of the ratchet levers remote from the pillar are each provided with an alined projecting pin 23, which in each instance passes through the inner end of an operating lever 24, the pin being headed beyond the lever 24, as at 25. A spring 26 is coiled about the pin 23 between the end of the ratchet lever and the operating lever. The respective operating levers 24 are pivotally mounted on pins 27 secured to a frame bar, such operating levers extending toward the front of the stand, but terminating short of the front plane. As the operating levers extend at right angles to the ratchet levers, the latter may be readily operated by the former when in cooperation with the teeth of the pillar, and as the operating levers are somewhat loosely mounted on pins 27, a swinging movement of the ratchet levers to withdraw the non-operating of such levers from the plane of the teeth is provided for.

The free ends of the operating levers do not extend beyond the face of the stand to permit such stand to be closed for protective purposes when not in use. In order to facilitate operation of such operating levers their free ends are made non-circular, and removable handles 28 are provided which may be fitted over the ends of the operating levers when desired or withdrawn for convenience in closing the stand.

Wall-like bodies 29 and 30 are arranged on the top of the frame, and spaced apart to provide a well on each side of the upper end of the pillar. These bodies present square flat top surfaces 31 providing work surfaces at the same heights above the top of the frame and their proximate walls 32 extend at right angles to the top 2 of the stand. One of these bodies, such as the body 30, is rigid with the frame of the stand, and the other has limited sliding movement relative to a frame 33 arranged within the body and secured to the stand top. The frame 33 includes a cross bar 34 fixed to the top of the stand and uprights 35 rising therefrom, the cross bar and uprights fitting in channels 33' in the inner surface of the wall body, as shown. The bottom bars 29' of the movable body 29 are attached to slide tongues 40 which move in guide slots or channels 41 which extend transversely of the top 2. Beneath the top 2 and at the side of the frame opposite from the body 29, the tongues are attached to a block 42, Figure 3, which moves against the under side of the top 2 and maintains the tongues in proper parallel re-

lation so that the desired movement thereof with the movable body 29, may be accomplished smoothly. Thus the movable body permits relative increase of the distance between the bodies, that is an increase in the width of the well to accommodate larger parts to be handled.

A platform 36 is removably secured to the upper end of the pillar 1 and is designed to support the articles to which glue is to be applied, and to operate more or less snugly in the well provided by the bodies 29 and 30. The platform is removable to permit the use of any size or form of platform that may be required in the particular gluing operation.

The slide floor 5 is of the full width and length of the stand, and is movable in the guides 4 to an extended position beyond the face of the stand, or moved rearwardly within the stand frame, the slide being slotted at 37 to pass the pillar 1. The slide is provided for the reception of the gluing accessories, being formed, for example with a ring 38 of a size and depth to receive an appropriate glue pot and with posts 39 on which a glue brush or brushes are or may be supported. When the slide is advanced these accessories are beyond the front of the stand convenient to the workman, with such accessories housed within the stand when the slide is moved inwardly.

It will be evident from the drawings and the above description, the pillar operating means is arranged within the stand immediately above the slide 5, so that when the removable handles 28 of the operating levers are withdrawn and the slide 5 moved inwardly, the front of the stand may be closed by a cover 40, removably secured in place, to thus prevent access to the operation of the pillar and protect the gluing accessories.

The gluing stand of the present invention is more particularly designed for the rapid and convenient gluing of the comparatively small lengths of wood used in certain bracing positions in aero-plane structure, though it will be understood that the stand is equally effective with other and dissimilar objects, and that any and all such uses are contemplated.

In use a series of such articles, referred to herein as sticks, are grouped on the platform 36, a plurality of such sticks being arranged side by side in a row and a series of rows piled one on the other. The cover plate 40 having been removed the operating lever 24 controlling the ratchet lever 17 is rocked on its pivot pin 27 to engage the headed end 25 of the pin 23 of that lever to withdraw the edge 19 from the plane of the pillar teeth 9. The other operating lever 24 is swung to compress the spring 26 of the other ratchet lever, lever 16, forcing the end of such lever at 18 into operative cooperation with the pillar teeth 8. The operating lever 24 cooperating with ratchet lever 16 is then oscillated in a direction on its pivot pin 27, to force the tooth-engaging end of the ratchet lever 16 upwardly and as this lever is in cooperation with the teeth, this movement will move the pillar upwardly to the extent of one tooth. The pillar can be moved downwardly by a similar movement of the other ratchet lever, it being important to understand that in each operation, the ratchet lever not being employed to move the pillar must be moved away from the plane of its teeth to prevent interference with pillar movement or injury to the teeth. The operating levers 24 are of course actuated through the use of the handles 28 which have been positioned for the purpose.

When the sticks have been arranged on the platform as described, the pillar is operated to raise the upper surfaces of the upper row of sticks somewhat above the top surfaces of the well-defining bodies 29 and 30. The slide floor 5 is then drawn outwardly, rendering the gluing accessories readily accessible, and the glue is applied to the exposed surfaces of the upper row of sticks. In the gluing position described the surfaces to be glued are above any part of the stand proper, may be easily treated, and the accidental application of the glue to the stand is largely if not entirely prevented.

The row of sticks to which glue has been applied is then merely slid off the next row below onto any convenient conveyor or table, exposing the upper surfaces of the next row of sticks. The pillar is again operated to raise the platform until the ten exposed surfaces of the sticks are at the desired and proper height, and the gluing is proceeded with.

It will be apparent that but a single workman is necessary for the complete gluing operation and as the sticks can be readily piled on the platform by the same workman when the platform is exhausted and also such workman or at least one other man may serve to remove the sticks to which glue has been applied, it is obvious that not only is the work facilitated, but fewer men for the same work under conventional practice are required to do effective work. Furthermore, the job is materially cleaner than heretofore, for no glue is wasted on the surrounding surfaces, and the surfaces to which the glue is to be applied stand up on a solid base to insure the most effective and rapid application of the glue.

The stand in its entirety is preferably quite small for convenience in movement from place to place where the gluing operation may be desired. However, there is no limitation in size contemplated, as the stand may be made, if desired, in a size to accommodate and effectively glue any desired object or series of objects.

Having thus described the invention, what is claimed as new, is:

1. A gluing stand including a frame having a top, a vertically adjustable pillar mounted for movement through said top, manually-operable means for adjusting the pillar, a platform secured on the pillar, wall members carried by the frame top and forming a well within which the platform is positioned for movement, one of the walls being adjustable with respect to the other to increase the width of the well to accommodate platforms of different widths, said walls having wide flat tops forming work surfaces.

2. A gluing stand comprising, a frame, the frame having a platform well therein, a platform movable in said well, means arranged within the

frame for selectively raising or lowering the platform, said well being defined by hollow bodies having relatively broad top surfaces disposed in a common horizontal plane, and one of said bodies being laterally adjustable on said frame.

3. A gluing stand comprising, a frame, the frame having a platform well therein, a platform movable in said well, means arranged within the frame for selectively raising or lowering the platform, said well being defined by hollow bodies having relatively broad top surfaces disposed in a common horizontal plane, and a guide support carried by the frame and fitting within one of said hollow bodies to permit limited adjustment of such hollow body relative to the other hollow body for adjustment of the width of the well.

4. A gluing stand having a platform for the articles to be glued, a pillar for supporting the platform, manually operable selective means for raising and lowering the pillar, a well in which the platform moves, means for adjusting one dimension of such well, friction means engaging the pillar to prevent its accidental movement under load, said pillar engaging means including a slide bar movable in a slot in and transversely of the pillar, a face plate on the slide bar to bear against one surface of the pillar, and a spring to exert tension on such face plate in its contact with the pillar.

5. A gluing stand comprising a platform, a pair of upstanding bodies mounted upon a table-like top in spaced relation and having opposed vertical walls forming a well, said top having an opening centrally between said bodies, a pillar mounted for vertical movement through said opening, a platform supported upon the upper end of the pillar above said top and within the well, said pillar having a series of upwardly facing ratchet teeth along one side and a series of downwardly facing ratchet teeth upon the opposite side, a pair of ratchet levers each supported upon a side of the pillar adjacent to and for engagement with a series of ratchet teeth, said ratchet levers being supported for oscillatory and longitudinal shifting movement, a spring connection between the ratchet levers normally drawing the same into operative connection with the ratchet teeth adjacent thereto, an oscillatable lever operatively coupled with each ratchet lever at the end thereof remote from the pillar for effecting both the oscillation and the longitudinal movement of the adjacent ratchet lever, the said upstanding bodies having flat tops disposed in a common horizontal plane, the platform being movable to a position in which its top surface is in the said common plane, and one of said upstanding bodies being movable relative to the other body for changing the width of the well.

RUBY R. ROLOSON.
